UNITED STATES PATENT OFFICE.

HERBERT C. TICE, OF NEWBURGH, NEW YORK.

DESIGN FOR A FLAGSTAFF-HOLDER.

46,417.

Specification for Design.

Patented Sept. 15, 1914.

Application filed July 17, 1914. Serial No. 851,848. Term of patent 14 years.

To all whom it may concern:

Be it known that I, HERBERT C. TICE, a citizen of the United States, and residing at Newburgh, in the county of Orange, State of New York, have invented a new, original, and ornamental Design for Flagstaff-Holders, of which the following is a specification, reference being had to the accompanying drawing, forming part thereof, in which—

view; and, Fig. 3 a front view of my newly designed flag staff holder.

I claim:—

The ornamental design for a flag staff holder, as shown.

HERBERT C. TICE.
